UNITED STATES PATENT OFFICE.

WILLIAM WEBSTER, OF MORRISANIA, NEW YORK.

IMPROVED BOILER-FEED REGULATOR.

Specification forming part of Letters Patent No. 40,523, dated November 3, 1863; antedated October 25, 1863.

To all whom it may concern:

Be it known that I, WILLIAM WEBSTER, of Morrisania, in the county of Westchester and State of New York, have invented a new and useful Improvement in Apparatus for Regulating the Quantity and Signalizing the Height of the Water in Steam-Boilers, &c.; and I do hereby declare that the following is a full and exact description thereof, reference being had to the accompanying drawings, which make a part of this specification.

The nature of my improvement consists of two parts: First, in the combined and mechanical arrangement of well-known devices, so constructed and operated that in consequence of the slightest expansion of a tube I am enabled, by means of a valve or pump, to supply and regulate the height of the water in steam-boilers.

The second part of my improvement consists in the application and use of a whistle or alarm, when operated by and connected about midway of and with the same expansive tube, by means of a clasp or other well-known device, that in consequence of the failure of the supply of water in the steam-boiler the expansion of the tube over and above that required to operate a valve or pump will reach or extend to that part of the tube to which the clasp is secured, and open the steam-valve to the whistle, which will admit the steam from the boiler to the whistle and sound an alarm.

The following is a description of its construction and operation, in which Figure 1 in the drawings represents a front view of my apparatus. Figs. 2 and 3 represent a side view of the brackets through which the tube passes. Figs. 4 and 5 represent a side view of a bracket and cap, which each end of the tube is screwed into, and one end is firmly held. Fig. 6 represents an edge view of an open mortise. Fig. 7 represents a side view of a clasp, and the letters herein refer to the said figures and to the parts of the said drawings; and Fig. 8, the steam-boiler.

A, Fig. 1, represents a brass tube, which is or about on a line with the water in the boiler, and passes through several brackets B loosely. One end of this tube is permanently attached to another bracket, C, which has an aperture through it into the tube, and to this bracket C is connected a water-pipe, D, which is to be

attached to the steam-boiler R, below the water-line, as shown at S. The other end of the tube A is permanently affixed to a cap, E, which has an aperture through it into the tube, and to this cap E is to be connected the steam-pipe T from the steam within the boiler R.

F and G, Fig. 1, represent two mechanical devices, which, in order to be understood, I will call "traversing-bars." One end of the bar F passes through the cap E, and is held on the outside by a screw-nut, a. The other end is attached to a wire or rod, b, which has a set-screw nut, V, or it may be attached to some other device in order to open a valve or shift a belt from one pulley to another pulley, such as are commonly used with pumps. The other traversing-bar, G, has one end passing through the clasp H, and is held by a screw-nut, e. This clasp is firmly clamped to the tube A by bolts. (See Figs. 1 and 7.) The other end of the bar has attached to it a standard, I, which is placed directly under and nearly against the valve-stem J of the steam-whistle K.

U is the steam-pipe to the whistle. This whistle, as well as the tube A, can be attached to the base or frame L in many different ways.

M M are two slotted brackets, in order that the apparatus can be adjusted to any height that the water may be required in the boiler.

N and O, Fig. 1, represent two pawls. One end of each is held within the open mortises P P by a screw-pin or bolt, which acts as and is a fulcrum to said pawls, as shown at e e. The other ends are tapered to a point and fit into notches in the angle part of the traversing-bars F and G, as shown at d d.

Q and Q', Fig. 1, are two other open mortises to guide and steady the traversing bars and pawls.

The apparatus to be properly adjusted to the height to which the water is required within the boiler is ascertained after the admission of the water and of the steam from the boiler into the tube A, to be expanded and contracted—viz.: Should I, by trying the second gage-cock, find steam and water, and also steam and water, as low down in the tube A as about one-half of its length, the apparatus is at its proper height, (some engineers carry more or less water than others; if so, the whole apparatus may be adjusted higher or lower,) but in adjusting the apparatus should the steam

in the tube A be farther than one-half way of the length of the tube toward the whistle, (which may be ascertained by wetting the finger and touching the tube,) then the apparatus wants to be adjusted lower, but should the water in the tube be pressing too hard on the steam end then adjust the apparatus higher. Now, after the apparatus has been adjusted according to the height of water the engineer wishes to carry it, and the valve should not open or close to admit or shut off the water to the boiler, or to operate the pump precisely, I regulate them by turning the set-screw nut V on the wire or rod b until the valve is opened or the pump is put on. When the water in the steam-boiler has decreased, the water within the tube A will also decrease—that is to say, the water within the tube will find its level with the water within the boiler through the water-pipe D, thus allowing the steam from the boiler through the steam-pipe T to enter the tube A, and in consequence of the temperature of the steam being higher than that of the water, which has just left that part of the tube, the tube is expanded lengthwise, carrying forward with it the cap E and the bar F, and in consequence of the resistance given to it by the pawl N, which acts as a fulcrum to the bar F, the other end of the bar, together with the wire or rod b, is drawn down, as represented by the dotted line, which will open a valve or operate on a belt to a pump. When water has again reached the desired height within the boiler, it will also increase within and fill the tube A, cooling and contracting it, thus allowing the bar F and wire or rod b to recede to its original position, also allowing the valve to be closed or the pump to cease working; but should the valve or pump fail

to work, or water fail to reach the boiler, and the water within the boiler still be decreasing, the steam within the tube A will expand, a farther part of it, to which is attached the clasp H, or its equivalent, carrying it forward, thereby opening the steam-valve to the whistle K, by means of the same and similar mechanical arrangement as used for the water—viz., the traversing-bar G, pawl O, and standard I will sound an alarm, and will continue to do so unless the steam is shut off from the boiler, or the water is again sufficiently raised within the boiler R and tube A.

An apparatus thus constructed and self-operating is of great utility, keeping the water in the boiler at a uniform height, saving a large per cent. of fuel, and is also a great safeguard against accident to the boiler.

Having fully described the construction, operation, and some of the many benefits arising from the use of my improved water-regulator and signalizer, I will proceed to describe what I claim.

What I claim as new, useful, and of my invention, and desire to secure by Letters Patent, is—

1. The combination of the traversing-bar, pawl, and expansive tube, as arranged, constructed, and operated, substantially as described, and for the purpose set forth.

2. In combination with the water-regulator, an alarm, when arranged, connected, and operated as described, and for the purpose set forth.

WILLIAM WEBSTER.
